VEIN STRIPPER WITH VARIABLE HEAD DIAMETER

Fred Vage Gunnar Ekbladh, Saro, Sweden, assignor to
Astra-Sjuco AB, Goteborg, Sweden

Filed Oct. 16, 1973, Ser. No. 406,830

Claims priority, application Sweden Apr. 19, 1973

Term of patent 14 years

Int. Cl. D24—02

U.S. Cl. D83—12 R

FIG. 1

FIG. 2

FIG. 3

FIG. 1 is an isometric view of the vein stripper with variable head diameter showing the nestable parts in separated condition as seen from the bottom of the head portion;

FIG. 2 is an exploded isometric view similar to FIG. 1, but from a different angle; and

FIG. 3 is an isometric view similar to FIG. 1, but with both heads nested together on the olive.

I claim:

The ornamental design for a vein stripper with variable head diameter, as shown.
